METHOD OF AND MEANS FOR BONDING
HEAT EXCHANGE CORESLe Fever M. Lee, Buffalo, N. Y., assignor to
Fedders-Quigan Corporation, Buffalo, N. Y.

Application March 16, 1942, Serial No. 434,874

6 Claims. (Cl. 263—40)

1

This invention relates to a method and means of bonding heat exchange cores of a type in which two fluids, such as air and water or air and air, respectively pass through and over a plurality of tubes to effect a temperature interchange through the walls of the tubes. More particularly, the invention is concerned with the provision of means for integrating a tube and fin or header assembly through localized fusion of bonding material at the joints.

For illustrative purposes, it may be recalled that heat interchangers of this class may be made by disposing a plurality of spaced parallel tubes between upper and lower header plates, and putting transverse or cross fins on the tubes if desired, as well as side plates and liquid receiving tanks on the headers. The metal of which the core is made may be coated with solder, if the material of construction is copper or brass, or with a special alloy of aluminum and silicon if the material is aluminum, so that, upon heating to a suitable temperature, the coating metal will melt or fuse, run into the interstices existing at the joints, and thus bond and integrate the core elements. Such integration is desired to impart strength and durability to the unit.

It has heretofore been proposed to effect the bonding action by subjecting the core assembly to blasts or drafts of hot air or products of combustion, the manufacturing operation being conducted in an oven or furnace. It has also been proposed, in certain types of hot air furnaces not adapted to take heat exchange cores, to reverse the direction of hot air flow periodically as a means of expediting the heat treatment. These prior art procedures and equipment are not satisfactory, however, for the integration of cores made of very thin metal, or of materials in which the fusion temperature is close to the melting point of the core metal.

Accordingly, it is among the objects of this invention to devise a method, or operating cycle, and apparatus, in which such cores may be subjected to a fusing temperature by hot air, delivered in such way that a close control may be exercised over the heating air, the time of heat treatment may be reduced, and the required power input held to a minimum. It has now been discovered that such objects may be attained by dividing the hot air flow through the core in such manner that a portion of the air flows in one of the available paths while the remainder of the air flows in the other of the available paths through the core, the two available paths, of

2

course, being those utilized for heat exchange purposes when the core is placed in service.

When such procedure is employed, particularly if it be combined with the reverse flow effect referred to above, deviations in temperature differentials throughout the core are brought to very small values, the time cycle is greatly curtailed, and the horsepower input made a fraction of that heretofore required. Apart from the savings in production costs so effected, the invention also permits the manufacture of such cores without the great loss heretofore encountered from burned or inadequately bonded assemblies, which, by reason of their imperfections, had to be rejected and scrapped.

The appended drawings show a hot air furnace in which the described method may be conducted, and for a fuller understanding of the invention, reference may be had to such drawings, 20 in which:

Fig. 1 is a view, partially in side elevation and partially in longitudinal section, through the furnace, and showing the divided air flow around the work;

Fig. 2 is a section taken on the line 2—2 of Fig. 1, or through the blower and heater end of the furnace; and

Fig. 3 is a section taken on the line 3—3 of Fig. 1, or through the work receiving end of the furnace.

In order to simplify the description, no discussion will be attempted of the electric circuits for controlling the motors, or supplying current to the electric heating elements, or regulating such circuits by control equipment, as these may be readily understood by those skilled in the electric furnace art. Similarly, the materials of construction are those commonly used, and need no specific description except to say this: when working with aluminum cores, fluoride fluxes may be specified. As these are somewhat corrosive against ordinary materials, the erection engineer should therefore specify materials of construction adapted to withstand such action. Otherwise, the furnace may be subjected to an unnecessary maintenance cost.

As shown in the several figures, particularly Fig. 1, the furnace comprises a box-like hearth portion 10 which is contiguous with a dome-shaped blower and heater portion 11. Both of these portions are framed on the exterior with sheets 12 and structural shapes 13, while the interior of the furnace is lined with heat-resistant ceramic material 14. This lining may, if desired in connection with minimizing corrosion, be

faced off with corrosion-resistant steel 15. The furnace, as thus far described, is formed internally with ducts and passageways through which the hot air may be circulated over and through the work.

The left hand end or blower portion 11 of the furnace is formed with an internal pedestal 16 receiving a bearing 17, and with an external support 18 mounted on one of the columns 13 which receives another bearing 19. These bearings are aligned to receive a blower shaft 21, driven by a motor 22 through suitable belts 23. A squirrel cage type blower 24 is mounted on the shaft 21 within the portion 11 to circulate the air.

In Figs. 1 and 2, the discharge side of the blower 24 is shown as delivering into a feed duct 26, while air is returned to the intake side of the blower through a duct 27, which is offset in order to supply returned air to both sides of the blower. To this end, the peripheral or discharge side of the blower 24 is shrouded by forming the liner 15 adjacent the inlet side 26 (which portion of the liner is here designated by the numeral 28) as a scroll which closely approaches the blower on its under side and diverges therefrom into the main portion of the duct 26. The duct 27 merges into a back duct 29 provided in the rear of the wall 28, which in turn terminates in a side chamber 31 disposed oppositely to the upper end of the duct 27. Air entering through the duct 27 therefore is divided by the back duct 29 and chamber 31 into two portions, and thus may enter the blower 24 from either side. As the air is driven by the blades of the blower, it emerges through the periphery into the chamber formed therebetween and the scroll 28, and so is directed into the feed duct 26.

The duct 26, adjacent the blower 24, is provided with a plurality of heating elements 33 which may conveniently be mounted on a panel section 34 which abuts the outer wall 12 of the furnace, and which protrude into the duct 26 through a side opening 35. During operation, the panel 34 is covered with a removable wall section 36 to avoid unnecessary heat losses and protect the heating elements from damage. The elements 33 may be of any desired type, either electric resistors or gas-fired quartz tubes, but for present purposes the resistor type is preferred. Current is supplied thereto in the usual way, and temperature-responsive regulators should be included in the circuits so as to maintain the air at the desired temperature.

The blower and heater portion 11, through the duct 26, merges into the hearth or work-receiving portion 10 at the lower end of the duct 26, and the arrangement of the portion 10 is such that the hot air is divided for dual flow through the work, and also reverse flow, before returning through the duct 27 to the blower 24 for recirculation and reheating. Some of the constituents of the portion 10 are: a perforate work supporting platform or hearth 41, upper and lower air passages 42 and 43 disposed in series through the platform 41, and means, such as a damper 44, for directing the hot air from the duct 26 through the passages and the platform and thence into the return duct 27.

It will be seen that the upper passage 42 is partially separated from the duct 26 by a depending wall 45, and is spaced from the return duct 27 by a bridge 46 formed with an overhanging portion 47 and a wall 48. The lower passage 43 is also separated from the return duct 27 by a bridge 49. Each passage, however, may be placed in communication with the ducts 26 or 27 through ter-

5 minal portions 42a, 43a, respectively, in which are located curved baffle plates 51, 52. Similar baffles 53 are disposed at the lower end of the duct 26 to direct the hot air uniformly into the passageways as conditions permit.

10 The platform 41 is formed as a grid of intersecting bars, and extends from the edge of the bridge 49 to the back wall 54 of the passage 43, baffles 55 in the passage serving to direct and distribute the air over the platform. The left hand portion of the platform, as it will be noted, underlies the overhanging section 47 of the upper bridge 46. The upper passage 42 is offset to the right, as indicated by the reference numeral 56, and it also contains flow-directing baffles or plates 57.

20 The side walls of the portion 10, as best shown in Fig. 3, are provided with aligned openings 61 adjacent the platform 41, and with sliding cover doors 62 guided between angle irons 63. The doors may be suspended by cables 64 passing over pulleys 65 mounted on an axle 66, which in turn is supported on posts 67 on top of the portion 10. Roller tracks 68 are positioned at either side of the furnace, at the level of the platform 41, so that the assembled cores C may be pushed in on one side, and withdrawn from the other.

25 The side walls of the portion 10, as best shown in Fig. 3, are provided with aligned openings 61 adjacent the platform 41, and with sliding cover doors 62 guided between angle irons 63. The doors may be suspended by cables 64 passing over pulleys 65 mounted on an axle 66, which in turn is supported on posts 67 on top of the portion 10. Roller tracks 68 are positioned at either side of the furnace, at the level of the platform 41, so that the assembled cores C may be pushed in on one side, and withdrawn from the other.

30 It will be seen, particularly from Fig. 1, that the core is so located in the furnace, on the platform 41, as to abut the overhanging end 47 of the bridge 46, and be spaced from the back region 56 of the passage 42. This accordingly and automatically provides a split or divided passageway from passage 42 to passage 43—namely, in a vertical direction through the core C, and in a longitudinal direction. When cores of varying sizes are to be treated, shut-off plates or adapters may be laid against and on the portion 47 or platform 41 as desired, so as to maintain this dual path. The construction just described is preferred to additional duct work for dividing the air current, because of its simplicity and adaptability to most conditions.

35 The above noted damper 44, employed to effect reversal or short-circuiting of the air path between the inlet 26 and the return duct 27, consists of a flat plate 71 mounted on a shaft 72 which is borne by an internal bushing 73 (Fig. 2) and a sleeve 74. Circular guards 75 are also positioned on the shaft adjacent the supported portions to reduce leakage along the sleeve and to protect the bearings from undue effects of the air current. The shaft 72 and the plate 71 are operated in unison by a small motor 76 driving a speed reduction gearing unit 77 to which the shaft is connected. This motor, depending upon the intended plan of operation, may be energized through automatically actuated controls to turn the damper 44 to one operative position, and then to the other by 90° rotation, and again to a neutral position, in timed sequence. Or, in some instances, such control may be dispensed with, and the positioning of the damper may be done manually.

40 In either event, it will be clear from Fig. 1 that the damper 44 may be disposed in any desired angular position. Thus, it may extend from the lower left corner of the bridge 46 to the diagonally opposite corner of the duct 26. In such case, flow will occur in the following circuit: From duct 26 into passage 42 via throat 42a, thence over deflectors 51 down through the core C, and simultaneously from end region 56 longitudinally of the core to the region under overhanging bridge portion 47. Both flows pass through adjacent portions of the open-work of

the platform 41 to merge in passage 43, and then flow through terminus 43a against the opposite surface of the damper 44 into return duct 27 for reheating.

On the other hand, if the damper is rotated 90°, then the plate 71 will extend from the lower edge of wall 45 to the diagonally opposite corner of lower bridge 49, and the air flow from the duct 26 to the return 27 will be just the reverse of that traced. The deflectors 55 will serve to divide the air stream, part of the air passing upwardly through the core, and the remainder passing through the apertures in the platform 41 for longitudinal flow. When the damper is placed midway between its terminal points, a short-circuiting path is provided between ducts 26 and 27 as a path of least resistance, and will thus minimize heavy losses of heated air when the doors 62 are opened to insert or remove a core.

Alternatively, or in connection with the short-circuiting of the ducts, the heat supplied to the elements 33 may be interrupted when the doors are opened, and the blower 24 may also be shut down. With heat exchange cores of the type hereinafter more specifically considered, one door 62 may be partially opened at the end of the heating period, and the work permitted to remain on the platform 41. If the heat input to the elements 33 is then interrupted, and the blower 24 continued in operation, a cooling draft of fresh air will enter the circuit, thus reducing the temperature of the work to a point where it may be handled with greater safety and convenience.

It has heretofore been noted that hot air furnaces, and devices for effecting a reversal of air flow, have heretofore been made, but none of them has been adapted to the development of the divided flow just described. In order to point out more clearly the significance of the new furnace, the steps or method of bonding a heat exchange core will be described.

For exemplary purposes, reference may be made to a tube and fin core assembly in which thin aluminum is used as the material of construction, the heat exchanger is formed with several hundred tubes, and it is desired to bond with aluminum-silicon alloy in order to integrate the structure. Since the alloy fuses at a temperature of say 1170°-1180° Fahr., and the metal itself will melt at about 1220°-1230°, it is apparent that a maximum temperature differential of only about 50° Fahr. is available, thus making the control of temperature an extremely difficult problem, even with modern precision instruments and regulators. It is, however, possible to hold the temperature of the air emerging from the duct 26 to a fairly close and satisfactory value. The problem therefore arises in limiting the temperature gradients through the core C itself, bringing all parts to temperature in a minimum of time, and avoiding such air velocities through the work as will tend to distort, and therefore injure, its relatively fragile structure at the high temperatures.

It will be apparent that the hot air blown over the work will lose some of its heat thereto, and thus, under ordinary conditions, and to bring the entire core up to bonding temperature at its most inaccessible points, it is necessary to overheat the core at the points of initial contact. Thus, in employing a single blast or air current, the possibility of burning cannot be eliminated. Similarly, it is now apparent that the customary reversal of air current, while serving to expose opposite surfaces to initial contact, still does not

suffice to reach the remote parts of the work in a satisfactory manner. By dividing the air stream for dual flow in intersecting directions through the core, and by superimposing the reversing effect, however, the maximum thermal paths from initial contact points to remote points is reduced to a minimum. This avoids the burning condition heretofore encountered, and also curtails the time required to bring the core up to temperature.

Another factor pertaining to the split or dual circulation relates to the power consumed in supplying the air to the hearth. In one type of furnace, as a comparative example, it was found that a fifty horsepower motor was required to operate a blower delivering 10,000 c. f. m. of hot air passing through the work in one direction. According to the present invention, however, wherein the air is divided into two streams, it is sufficient, for the same size core, to supply 7,000 c. f. m. at the same temperature, using the input of a ten horsepower motor. The explanation of this surprising reduction in power consumption is in the circumstance that since the heating air has a much greater area through which to pass, it may pass through the core with less resistance or pressure drop. Since the power input rises as the cube of the resistance, the dual paths permit the accomplishment of the desired result with less air and less power.

In applying this method to heat interchangers as described, the work C is inserted into the furnace onto the platform 41, the damper 44 being then at a neutral or short-circuiting position. The doors 62 are closed, and the damper is turned to one of its diagonal positions to direct the air flow through one or the other of the effective paths. Since the core C may be readily located on the platform, the dual paths are automatically determined, as heretofore described. Reversal of flow can be effected by the settings of the motor 76, and it may be any value found suitable by experience. Thus, if the core can be brought to temperature in six minutes, the damper 44 may be reversed every half minute, and for a nine minute heating cycle, reversals may be made every minute. As soon as the whole work has been brought to the bonding temperature, the damper should be returned to neutral, and the work removed, since prolonged heating may be actually detrimental and could serve no beneficial purpose.

For other types of work, it will be apparent that the cycles will be modified to suit the occasion, and it will also be apparent that under some conditions the reversal of flow may be omitted, since the savings incident to the provision of dual pathways may be obtained without resort to this step. The great advantage of reversing is, of course, to shorten the time cycle.

It will also be apparent to those skilled in the art that while the invention has been described with reference to one specific form of apparatus and the processing of a designated type of core, the principles may be otherwise embodied, and therefore it is intended that the foregoing description be considered as illustrative, and that the scope of the invention should not be restricted thereto, but should be deemed commensurate with the following claims.

I claim:

1. A hot gas furnace having a blower portion including a blower and heating means for circulating and heating air, inlet and return ducts respectively delivering the air from and induct-

ing it to the blower, and a hearth portion connected to the blower portion through said ducts, said hearth portion including a pair of spaced passages, a perforate platform positioned between the passages, one of said passages having an offset portion and an overhanging portion whereby, when work is placed on the platform in abutting relation to the overhanging portion a dual flow path may be established between said passages, and means for connecting one of said passages with the inlet duct and the other of said passages with the return duct.

2. A hot gas furnace comprising a hearth portion having a pair of spaced passages, a perforate platform positioned between the passages, one of said passages having a portion laterally positioned with respect to the platform, a bridge member disposed in one of said passages and overhanging a portion of the platform thereby to provide, with respect to work positioned on the platform, dual paths between said passages, inlet and return ducts respectively connected to the passages, a blower portion communicating with the opposite ends of the ducts, and means in the blower portion for heating and recirculating the hot gas to said passages.

3. A hot gas blast heating furnace comprising a hearth portion and a blower portion and ducts extending between and through said portions to form a cyclic flow path, said hearth portion having a pair of spaced passages forming parts of the path, a work-receiving platform positioned in the hearth portion and dividing the passages from each other, an inlet duct and a return duct spaced from said platform, each of said ducts being in open communication with said spaced passages, a damper movable to connect the inlet duct with one or the other of the passages and the return duct with the other or one of said passages, said inlet and return ducts extending to said blower portion, a blower mounted in the blower portion, said blower having a suction side and a discharge side, said return duct terminating in the blower portion at the suction side thereof, said inlet duct connecting with the discharge side of the blower, and air heating means disposed in the inlet duct between the discharge side of the blower and said damper.

4. A hot gas blast furnace comprising an elongated portion having an internal end wall provided with a horizontal section, a pair of bridges disposed transversely of the portion remote from

the said end wall, a perforate platform extending from said horizontal section to one of said bridges, flow passages formed in the portion above and below the platform and bridges, one of the bridges overhanging a portion of the platform, a work entry opening in the portion to permit the placement of work on the platform between the horizontal section and the overhanging bridge, a blower and heater portion disposed contiguously to the elongated portion, ducts extending between said portions, and means for connecting the ducts and passages in a closed circuit extending through the platform.

5. A hot gas furnace comprising a box-like structure having a blower portion and a hearth portion, means in the hearth portion to support work to be heated by the hot gas and passages adjacent said supporting means to receive hot gas from and return it to said blower portion, said blower portion including a dome, a rotary blower mounted in the dome, a scroll surrounding the periphery of the blower and terminating in an inlet duct, said inlet duct extending from said dome to the hearth portion and communicating with at least one of the passages therein, heating elements mounted in the duct to supply heat to the gas delivered by the blower, a back duct behind the scroll and merging into side chambers at either side of the blower, and a return duct communicating with the back duct and side chambers and extending to the hearth portion and communicating with at least one of the passages therein.

6. A hot gas furnace comprising a blower and heater portion and a hearth portion, said blower portion being located at the end and partially to one side of the hearth portion, upper and lower passages formed in the hearth portion, said passages being divided by a work-receiving platform and being separated by upper and lower bridges, a return duct extending from between the bridges to the blower portion, an inlet duct extending from the blower portion to the hearth portion, said inlet duct and passages being located in quadrant positions to each other, a rotary damper mounted between the duct and passages adjacent the bridges, and means for rotating the damper to different angular positions to connect the inlet duct and the return duct successively to first one passage and then the other.

LE FEVER M. LEE.
